DESIGN FOR A SEPARABLE BROOCH

Oscar Placco, Cranston, R. I., assignor to Cohn
Rosenberger, Inc., New York, N. Y.

Application July 21, 1938, Serial No. 78,628

Term of patent 3½ years

To all whom it may concern:

Be it known that I, Oscar Placco, a citizen of the United States of America, residing in Cranston, county of Providence, and State of Rhode Island, have invented a new, original, and ornamental Design for a Separable Brooch, of which the following is a specification, reference being had to the accompanying drawing, forming part thereof.

Fig. 1 is a plan view of a separable brooch showing my new design.

Fig. 2 is an edge view thereof.

Fig. 3 is a plan view in open position.

I claim:

The ornamental design for a separable brooch, substantially as shown.

OSCAR PLACCO.
